CLAIM

The ornamental design for a slide carrier, as shown and described.

DESCRIPTION

FIG. 1 is a perspective view of a slide carrier;

FIG. 2 is a top view thereof;

FIG. 3 is a bottom view thereof;

FIG. 4 is a side view thereof;

FIG. 5 is another side view thereof;

FIG. 6 is a front view thereof; and,

FIG. 7 is a back view thereof.

The broken lines are included for the purpose of illustrating portions of the slide carrier that form no part of the claimed design.
